DESIGN FOR A FIRE-PLACE.

Design No. 13,449, dated November 21, 1882.

UNITED STATES PATENT OFFICE.

WILLIAM C. PEET, OF JERSEY CITY, NEW JERSEY, ASSIGNOR TO THE J. L. MOTT IRON WORKS, OF NEW YORK, N. Y.

DESIGN FOR A FIRE-PLACE.

SPECIFICATION forming part of Design No. 13,449, dated November 21, 1882.

Application filed October 17, 1882. Term of patent 7 years.

To all whom it may concern:

Be it known that I, WILLIAM C. PEET, of Jersey City, in the State of New Jersey, have invented a certain new Design for Fire-Places, 5 of which the following is a specification.

This fire-place, frame, and fender are similar in ornamentation, and with the andirons compose a complete design, as shown in the annexed engraving. The entablature of the fire-place frame has a central sunflower ornament, *a*, and the panels are ornamented with sunflower and cinquefoil leaflets, as at *b* and *c*. The ornamental brackets *e* are above the capitals *f* of the columns *g*. These have leaflet bases *h*, as represented. The architrave has leaflet ornaments and bars, as at *k*, and there are bracket-pieces *l*. The andirons have triple-flower ornaments *m*, stems *n*, side arches, *o*, and leaflet ornaments *p* with paneled bases, as 10 shown. The fender-piece has a banded-rod border, *q*, echinus base *r*, urn ornaments *s*, with pineapple-heads and leaflet panels, as in 15 the engraving. The paneled surface of the fender is ornamented to correspond to the 20 tablature, or nearly so, as shown, the same letters of reference being used. The wings of the fender are curved backwardly at the base and made with pedestals *u* and winged lions *v*, as represented. The surfaces of the sides 25 and back of the fire-place are ornamented with 30 diamond-shaped leaflets, as represented at *w*.

I claim as my invention—

1. The design of the circular ornament *a* and flower and leaflet ornaments *b* *c*, substantially as shown. 35
2. The design of the fire-place frame, composed of the entablature, the brackets *e*, capitals *f*, columns *g*, and bases *h*, substantially as represented.
3. The design of the architrave *k* and brackets *l*, as represented. 40
4. The design of the andirons, consisting of the triple flowers *m*, stems *n*, arches *o*, and leaflet ornaments, substantially as shown.
5. The design of the fender, consisting of 45 the urns *s*, banded-rod border *q*, and echinus base *r*, substantially as shown.
6. The design of the fender-wings, consisting of the bases *u* and winged lions *v*, as represented. 50
7. The design of the diamond-shaped leaflets on the surface of the sides and back of the fire-place, as represented.

Signed by me this 13th day of October, A. D. 1882.

WILLIAM C. PEET.

Witnesses:

WILLIAM G. MOTT,
GEO. T. PINCKNEY.
